UNITED STATES PATENT OFFICE.

HENRY P. MERRIAM, OF NEW YORK, N. Y.

FUSE FOR PROJECTILES.

SPECIFICATION forming part of Letters Patent No. 630,622, dated August 8, 1899.

Application filed January 21, 1899. Serial No. 702,916. (No model.)

To all whom it may concern:

Be it known that I, HENRY P. MERRIAM, a citizen of the United States, residing at New York, in the county and State of New York, 5 have invented certain new and useful Improvements in Fuses for Projectiles, of which the following is a specification.

In an application filed by me October 26, 1898, Serial No. 694,587, I have covered a fuse 10 for projectiles consisting, broadly, of a fuse-body adapted to be secured in the base of a projectile and formed with a hammer-chamber and a bolt cavity or socket, a hammer supported in the chamber and having a se- 15 curing pin or shank connected with and pro- jecting from it through a suitable opening into the bolt socket or cavity transversely of the path of movement of the bolt and con- structed and arranged to yield and break un- 20 der a transverse bending strain, and a bolt supported in the bolt cavity or socket and ex- posed to the gas-pressure of the propelling charge of the gun to be forced thereby against the securing-pin to bend the pin laterally 25 and break it off from the hammer to thereby release the hammer in its chamber. Nor- mally the hammer is supported in inoperative position in one end of its chamber by the se- 30 curing-pin, which is suitably held in the bolt cavity or socket. In the form of fuse shown and described in said application the sec- 35 uring-pin is held against transverse movement at the hammer end by its engagement with the hammer and the wall of the opening com- municating between the hammer-chamber and bolt cavity or socket, while a spherical head on the end of the securing-pin rests freely in the bolt cavity or socket and is ex- 40 posed to the transverse bending strain ex- 45 erted upon it by the bolt when the latter is forced forward in its cavity by the gas-pres- 50 sure of the propelling charge of the gun, whereby the securing-pin is bent transversely until it breaks adjacent to the hammer, and the hammer is released in its chamber in readi- 55 ness to detonate the primers when the shell strikes the target. My present invention is an improvement upon the fuse covered by said above-named application and operates 60 upon the same general principle, in that the

hammer is supported in inoperative position in its chamber by a securing-pin which is suitably held in the bolt cavity or socket and constructed and arranged to yield and break under a transverse bending strain exerted 55 upon it by the bolt when the projectile is fired from the gun.

The object of my present invention is to simplify and improve the structure and opera- 60 tion of this style of fuse for projectiles.

The fundamental principles upon which the operation of my improved structure de- 65 pends may be briefly stated as follows: When a rod or pin moves laterally around a point more or less distant, the velocities of move- 70 ment of the various sections of the rod or pin vary proportionally to the distance of said sections from the said point. If the above rod, to be referred to as a "first part," be now imagined to be prolonged by successive short 75 sections, still keeping one piece of metal, and the velocity of each of the successive sections of this second part varies gradually from that of the part of the rod immediately preceding it and proportionally to the distance of such 80 section from some point not coincident with the center for the first part of the rod, then a bending of the rod is produced at the point between the first and second parts. In ap- 85 plying these principles to the breaking of the metal retaining pin or shank which secures the hammer in inoperative position in a fuse it will be clear that if the bending action is confined to a sufficiently short section to over- 90 come the tensile strength of the material a 85 rupture of the pin or shank will take place. I claim, broadly, the application of these principles to the construction of fuses for projectiles.

In my present invention the securing-pin 90 (constructed to break under a transverse bending strain) is suitably connected with the hammer to normally restrain it from denotat- 95 ing the primers and extends freely through an enlarged opening from the hammer-cham- 95 ber to the bolt cavity or socket, wherein it is suitably supported and exposed to the action of the hammer-releasing bolt or piston, which by reason of the arrangement and construc- 100 tion of the pin and supported hammer in the

fuse-body imparts a sufficient transverse bending strain to the pin to break it and release the hammer in its chamber. The pin is connected with the hammer, so as to have a slight rotary movement laterally of the fuse-body either with the hammer or independently of the hammer, and is secured in the bolt socket or cavity either by a connection directly with the bolt or piston or by a connection with the fuse-body or by other means which will allow it lateral movement in the opening between the hammer-chamber and bolt cavity or socket when acted upon by the bolt or piston. When the bolt or piston is forced forward in its socket or cavity by the pressure of gas of the propelling charge of the gun, the securing-pin will be forced laterally in front of the bolt or piston, and as the pin must move in a rotary direction around a point at or adjacent to its hammer end and when connected directly with the bolt in a rectilinear direction at its opposite end or (when connected with the fuse-body at said opposite end) in a rotary direction around its point of connection with the fuse-body at said opposite end it will be subjected to an effective transverse bending strain and will break adjacent to the hammer to release the hammer in its chamber. The opening communicating between the hammer-chamber and bolt cavity or socket is enlarged to allow free lateral movement of the securing-pin in the fuse-body, the pin being confined only by its connection with the hammer and bolt or fuse-body in the bolt cavity or socket. Said opening is preferably an elongated slot extending in the direction of the bolt cavity or socket. The securing-pin is preferably screw-threaded to render it sensitive to lateral strain and also to provide a simple and convenient means of attachment to the hammer and bolt; but the pin may be otherwise connected with the hammer and bolt (or fuse-body) and rendered sensitive to the breaking transverse bending strain by a cut or groove at the desired breaking-section.

The preferred forms of construction of my improved fuse and their operation will be hereinafter fully described in detail with reference to the accompanying drawings and the novelty will be particularly pointed out in the annexed claims.

In said drawings, Figure 1 is a sectional view of a shell representing the preferred form of my improved fuse applied thereto, the parts being in the position assumed before the shell is fired. Fig. 2 is a similar view of the fuse, showing the hammer liberated and in the position assumed when detonating the primers at the instant the velocity of the shell is suddenly checked, as when striking a target. Fig. 3 is a view similar to Fig. 1, showing a slightly-modified structure, the parts being in normal inoperative position. Fig. 4 is a detail plan view of the cap con-

taining the quick-burning charge. Figs. 5, 6, and 7 are views similar to Fig. 1, showing further-modified forms of my improved fuse, the parts being in normal inoperative position in each case. Figs. 8, 9, and 10 are diagrammatic views illustrating the breaking action of the hammer-securing pin.

Referring first to Figs. 1, 2, and 4, the shell 1 is formed in its base with an interiorly-threaded opening, into which the body 2 of my improved fuse is screwed. The fuse-body 2 is formed with a hammer-chamber 3, having a hemispherical lower portion 3^a, in which the spherical hammer 4 normally rests. 6 is 80 the hammer-securing pin or shank, preferably screw-threaded from end to end for the double purpose of making the pin sensitive to a transverse bending strain and for facilitating the rigid attachment of the pin with 85 the hammer and bolt. The hammer 4 is formed with a threaded radial opening 5, into which one end of the threaded pin 6 is screwed. If desired, the pin 6 may be formed with a nicked head and extend entirely through the 90 hammer, as indicated in dotted lines in Fig. 1, in which case the head of the pin will confine the hammer upon the pin and the lower end only of the pin need be threaded. The pin 6 extends from the hammer 4 through 95 an enlarged opening 8, leading from the hammer-chamber into the bolt cavity or socket 7, which is formed in and extends transversely of the body of the fuse and is open at one end to expose the firing bolt or piston 9 to the 100 pressure of the gases of the propelling charge of the gun. The bolt or piston 9 is formed with a transverse interiorly-threaded opening 10, into which the lower end of the securing-pin 6 is screwed. The opening 10 in the bolt 105 9 may be directly transverse to the length of the bolt, or it may be inclined more or less to the transverse diameter in the direction of movement of the bolt, it being preferable to have the opening slightly inclined to support 110 the securing-pin in inclined position to facilitate the breaking of the pin, as will be clear from the hereinafter-given explanation of the operation. The opening 8, leading from the chamber to the bolt cavity or socket, is considerably larger than the diameter of the securing-pin to allow free lateral movement of the securing-pin at the moment of firing the shell to facilitate the breaking of the pin in accordance with my invention. Said opening 115 8 is preferably in the form of an elongated slot extending in the direction of the bolt cavity or socket. It will be clear from the description as far as gone that in the form of fuse now being described the securing-pin is 120 held at its opposite ends in the hammer and firing-bolt, while it is free in the opening communicating between the hammer-chamber and bolt cavity or socket. By reason of the 125 spherical shape of the firing-hammer and the hemispherical lower portion of the hammer-chamber the hammer is capable of only a 130

slight movement in a rotary direction in the seat of the hammer-chamber, while the firing bolt or piston being of cylindrical shape and supported in a cylindrical bolt cavity or socket is capable of moving only in a rectilinear direction. The divergent paths of movement of the hammer and firing-bolt having the pin secured to them prevent the various sections of the pin from moving at velocities proportional to the distance of such sections from the center around which the hammer moves, thereby subjecting the pin to a severe transverse bending strain, which results in the breaking of the pin and the release of the hammer in its chamber. 12 is the usual soft-metal gasket or thimble fitting snugly in the open end of the bolt socket or cavity 7 to prevent the passage of powder-gases past the bolt 9 into the hammer-chamber. The bolt or piston 9 is of sufficient length to shut off communication between the opening 8 and open end of the bolt cavity or socket to further insure against the entry of powder-gases to the hammer-chamber. 25 The inner end of the fuse-body 2 is interiorly threaded for the reception of the annular head or primer-carrier 20, which is formed with an annular combustion-chamber 22, in which is supported a quick-burning charge 23 and a series of sockets 21, in which are mounted the primers or fulminate patches 24, resting against firing-lugs 25. 26 are ball-firing pins secured in the sockets 21 in contact with the primers 24. The primers are in direct communication with the annular combustion-chamber 22. The chamber 22 is closed by the circular perforated plate 30, which is secured in the open end of the annular combustion-chamber by upsetting the metal of the primer-carrier 20. The inner face of the primer-carrying head 20 is dished or formed with a conical socket in which the ball-receiving openings 21 are formed. In the center of the conical socket is formed a cylindrical recess in which rests a small conical spring 50, which is adapted to engage the hammer 4 for steadyng it and preventing its knocking against its casing during flight and insuring a maximum force of impact of the hammer against the primers when the shell strikes the target. When the velocity of the shell after firing is retarded, as when striking a target, the spring 50 is easily compressed by the hammer and does not appreciably interfere with the detonation of the primers.

Referring to Fig. 3 of the drawings, it will be observed that the hammer-securing pin 6 is secured to the hammer and firing-bolt, as in the form shown in Figs. 1 and 2; but in this modified form the securing-pin is inclined to a greater degree to increase the transverse bending strain exerted upon the securing-pin when the projectile is fired.

In the modified form shown in Fig. 3 the structure of the primer-carrier is also somewhat different from the preferred form above

described. In this form I employ a single primer 35, mounted in a central socket in the primer-head 20 and communicating with the annular combustion-chamber 22 through one or more inclined passages 36. A single ball-firing pin is mounted in the central socket of the primer-head in contact with the primer. The conical spring 50 of the preferred form of fuse is omitted and in its place a spider-shaped spring 38 is substituted for engaging and steadyng the hammer in its chamber during flight of the shell.

In the form of fuse shown in Fig. 5 the hammer-securing pin or shank 6 is integral with or otherwise rigidly attached to the spherical hammer 4 and projects radially from the hammer through enlarged opening 8 into bolt cavity or socket 7 and secured at its lower end in the wall of the bolt cavity or socket, preferably by a threaded engagement therewith. The pin has an annular cut or groove 6^a between its ends and is engaged at or adjacent to the cut or grooved section by the bolt or piston 9, which has a vertically-beveled forward end. The hammer-chamber is formed the same as in the form shown in Fig. 1 to allow a slight rotary movement of the hammer therein. When the bolt is forced forward in its cavity, the central reduced section of the securing pin or shank will be forced laterally in front of the bolt, the transverse sections of the pin on either side of the reduced section moving proportionally to their distance from two points, (the center around which the hammer turns and the point of attachment of the lower end of the pin with the fuse-body in the bolt cavity or socket,) producing a transverse bending strain which is concentrated at the reduced section of the pin, causing the pin to break at said section to release the hammer in its chamber. The structure shown in Fig. 5 is designed to operate with a primer-head such as shown in either Fig. 1 or Fig. 3.

In Fig. 6 the hammer-chamber 3 is of cylindrical shape, having the slot or opening 8, leading to the bolt cavity or socket. The hammer 4 is of approximate pear shape, with its enlarged impact end fitting the hammer-chamber and its reduced end resting loosely in the end of the hammer-chamber adjacent to the bolt cavity or socket and free to move laterally. A headed securing-pin passes through an axial opening in the hammer and is screwed into the bolt or piston 9, whereby it is supported to retain the hammer in inoperative position in its chamber. The hammer has an impact-head 4^a and is adapted to operate with a primer-head having a single centrally-located primer, such as in Fig. 3. In this form of fuse the action of breaking the securing-pin is the same as with the forms shown in Figs. 1, 2, and 3, the hammer moving in a rotary direction, while the bolt moves in a rectilinear direction.

In Fig. 7 the fuse-body is of the same con-

struction as in Fig. 6, but the hammer is of cylindrical shape, loosely fitting the hammer-chamber and formed with an axial opening 4^c, which flares or enlarges toward the bolt end. A headed securing-pin 6 passes through the flaring opening 4^c and is screwed into the bolt 9. The head of the pin engages an internal shoulder 4^d in opening 4^c for confining the hammer. A firing-pin 4^e is attached to the head of the hammer in position to detonate the primer supported in a primer-head in any suitable manner. In this form of the fuse the firing-pin ball is omitted from the primer-head to allow firing-pin 4^e to detonate the primer. In this form of fuse the pin is capable of a slight movement in a rotary direction independently of the hammer, which cannot move laterally, the flaring axial opening in the hammer allowing the movement of the pin.

In Fig. 8 I have represented diagrammatically the successive positions of the parting-sections of the securing-pin during the breaking-action in the forms of fuses shown in Figs. 1, 2, and 3. *a* indicates the portion of pin moving with the hammer in a rotary direction, while *b* indicates the portion of pin moving rectilinearly with the bolt or piston. *c* is the point of rupture due to the bending strain.

In Fig. 9 I have shown in a similar manner the breaking action of the pin in the form of fuse shown in Fig. 5, in which the sections upon either side of a reduced section move proportional to their distance from two points, the center of rotation of the hammer and the point of attachment of the lower end of the pin with the fuse-body. *a* and *b* indicate the parting portions, and *c* the section of rupture.

In Fig. 10 I have shown the breaking action in the forms of fuse shown in Figs. 6 and 7, which is very similar to the action illustrated in Fig. 8.

The operation of my improved fuse as shown in Figs. 1, 2, 3, and 4 will now be described. The fuse being applied to the projectile with the parts in the position shown in Fig. 1, the projectile is fired from the gun. The pressure of the exploded propelling charge of the gun which expels the projectile therefrom forces the bolt or piston 9 longitudinally in its socket or cavity 7, the bolt or piston traveling rectilinearly and tending to carry the securing-pin and connected hammer in the same direction, causing the hammer to rotate slightly in the hemispherical seat 3^a in the lower part of the hammer-chamber, the result being the application of an effective transverse bending strain upon the securing-pin between the bolt and hammer, which breaks the pin at this point and releases the hammer in its chamber. The effectiveness of the transverse breaking strain upon the securing-pin is due to the divergent paths of movement of the bolt and hammer, which prevents the various transverse sections of the securing-pin from moving at velocities

proportional to their distance from the center around which the hammer moves. During the flight of the projectile the hammer 4 rests under the force of the spring 50 or 38 in the hemispherical recess 3^a of the hammer-chamber. As soon as the projectile strikes the target its velocity will be suddenly checked and the hammer 4 will be forced to the inner end of its chamber, compressing the retaining-spring and striking one or more of the firing-pin balls. The percussion of hammer 4 against one of the firing-pin balls detonates one or more of the primers, and the flash from the primers passes into the combustion-chamber 22, ignites the quick-burning charge therein, and the flash from said charge communicates with the bursting charge of the projectile.

The principal useful and desirable result derived from my improved arrangement is the greatest possible safety with a given force available for releasing the hammer, whereby the hammer can be more effectively secured against accidental release previous to the firing of the shell. It is evident that the limit of the force holding the hammer in its seat in the fuse-body is the direct tensile strength of the smallest cross-section of the retaining pin or shank, and the strain set up by accidental shocks to which the fuse is subjected previous to firing, which would tend to release the hammer in its chamber, would almost entirely be that of direct tension upon the pin or shank, while the force necessary to the release of the hammer in its chamber is a transverse bending force controllable by a sharp groove or thread cut in a single short section of the pin or shank. The disparity between these two forces can be readily shown by taking a small metal rod, preferably steel, having a sharp circumferential groove cut into it at a point midway of its length. To break this grooved rod by a transverse bending strain concentrated at the reduced section would require only a small fraction of the force necessary to disrupt the rod by direct tension or shearing.

By the expression used in the specification and claims "the securing pin or shank connected with the hammer" I mean to cover any and all means of connecting or joining the securing pin or shank and hammer, whether the pin or shank is screwed into the hammer or is formed integral with the hammer, or passes loosely through the hammer and confines the hammer upon it by means of a head or enlargement or other confining means or any other connection whereby the hammer is supported in its chamber by the pin or shank.

I consider my above-described invention subject to the broad claims contained in my above-named application, filed October 26, 1898, Serial No. 694,587, in that the hammer is supported in inoperative position in its chamber by a securing-pin held in the bolt cavity or socket and constructed to yield and

break under a transverse bending strain exerted upon it by the firing-bolt. My present invention differs, broadly, from the invention covered by said application in that the trans- 5 verse bending strain for breaking the securing-pin is exerted by the divergent paths of movement of the parts of securing-pin adjacent to the hammer and bolt, and I claim this distinction broadly in my present case.

10 Having thus described my invention, what I claim as new therein, and desire to secure by Letters Patent, is—

1. In a fuse for projectiles, the combination of a fuse-body having a hammer-chamber and a communicating bolt cavity or socket, a hammer supported in its chamber, a bolt or piston supported in the bolt cavity or socket and arranged to be exposed to the gas-pressure of the propelling charge of the gun, and a ham- 15 mer-securing pin, sensitive to lateral bending strain, and connected with the hammer and held in the bolt cavity or socket; the hammer, the bolt and the hammer-securing pin being constructed and arranged to cause one 20 portion of the pin to move in a lateral rotary direction with relation to a point more or less distant and restrain another portion of the pin from moving proportionally to its distance from said point, whereby the pin will be sub- 25 jected to a breaking transverse bending strain, substantially as set forth.

2. In a fuse for projectiles, the combination of a fuse-body having a hammer-chamber and a communicating bolt cavity or socket, a hammer supported in its chamber, a bolt or piston supported in the bolt cavity or socket and arranged to be exposed to the gas-pressure of the propelling charge of the gun, and a ham- 30 mer-securing pin connected with the hammer and bolt and sensitive to lateral bending strain; a portion of the hammer-securing pin being adapted to move in a lateral rotary direction with regard to a point more or less distant, and another portion of the pin being 35 adapted to move in a divergent path dispropor- 40 portionately to its distance from said point, whereby the pin is subjected to a breaking bending strain, substantially as set forth.

3. In a fuse for projectiles, the combination 45 of a fuse-body having a hammer-chamber and a communicating bolt cavity or socket, a hammer supported in its chamber, a bolt or piston supported in the bolt cavity or socket and arranged to be exposed to the gas-pressure of the propelling charge of the gun, and a ham- 50 mer-securing pin connected with the hammer and bolt and sensitive to lateral bending strain; the hammer and bolt being arranged to move in divergent paths or directions when 55 the bolt is forced forward in its cavity or socket by the gas-pressure of the propelling charge of the gun, substantially as set forth.

4. In a fuse for projectiles, the combination 60 of a fuse-body having a hammer-chamber and a communicating bolt cavity or socket, a ham- 65 mer-supported in its chamber, a bolt or pis-

ton supported in the bolt cavity or socket and arranged to be exposed to the gas-pressure of the propelling charge of the gun, and a ham- 70 mer-securing pin connected with the hammer and bolt and sensitive to lateral bending strain, and passing freely through the opening communicating between the hammer-chamber and bolt cavity or socket, the bolt being capable of moving rectilinearly under 75 the gas-pressure of the propelling charge of the gun while the hammer is capable of moving only in a rotary direction under the action of the bolt exerted through the securing-pin, substantially as and for the purpose set forth. 80

5. In a fuse for projectiles, the combination of the fuse-body having a hammer-chamber and a bolt cavity or socket, a hammer in the hammer-chamber, a bolt in the bolt cavity or socket arranged to be exposed to the gas-pres- 85 sure of the propelling charge of the gun, and a hammer-securing pin, sensitive to lateral bending strain, connected at its opposite ends with the hammer and bolt and passing freely through an opening communicating between 90 the hammer-chamber and bolt cavity or socket and inclined to the transverse diameter of the bolt, substantially as set forth.

6. In a fuse for projectiles, the combination of the fuse-body having a hammer-chamber formed with an approximately hemispherical lower end and a bolt cavity or socket extending transversely of the hammer-chamber and communicating therewith through a slot or elongated opening extending in the direction 100 of length of the bolt cavity or socket, a spherical hammer supported in the hammer-chamber, a bolt or piston in the bolt cavity or socket, and a hammer-securing pin sensitive to transverse bending strain secured at its 105 opposite ends to the hammer and bolt and extending through the slot or elongated opening, substantially as set forth.

7. In a fuse for projectiles, the combination of a fuse-body having a hammer-chamber 110 and a bolt cavity or socket communicating through an enlarged opening, a spherical hammer in its chamber having a limited ro- 115 tary movement and confined against direct lateral movement by its engagement with the wall of the hammer-chamber, a bolt in its cavity or socket having a rectilinear move- 120 ment, and a securing-pin sensitive to trans- 125 verse bending strain and connected at its ends with the hammer and bolt, whereby, when the bolt is forced forward in its cavity or socket by the firing of the projectile from the gun, the hammer moving only in a rotary direction and the bolt moving only in a linear direction, the hammer-securing pin will be strained and bent laterally until it breaks to free the hammer in its chamber, substan- 130 tially as set forth.

8. In a fuse for projectiles, the combination of a fuse-body having a hammer-chamber 130 and a communicating bolt cavity or socket, a hammer supported in its chamber, a bolt

or piston supported in the bolt cavity or socket and arranged to be exposed to the gas-pressure of the propelling charge of the gun, and a hammer-securing pin connected with 5 and extending radially from the hammer and rigidly attached to and extending in a transversely-inclined direction from the bolt, said pin being sensitive to lateral bending strain; the hammer and bolt being arranged to move

in divergent paths or directions when the bolt 10 is forced forward in its cavity or socket by the gas-pressure of the propelling charge of the gun, substantially as set forth.
